DESIGN FOR AN IDENTIFICATION EMBLEM

Lafayette F. Cargill, Michigan City, Ind.

Application December 4, 1935, Serial No. 59,907

Term of patent 14 years

To all whom it may concern:

Be it known that I, Lafayette F. Cargill, a citizen of the United States, residing at Michigan City, in the county of La Porte and State of Indiana, have invented a new, original, and ornamental Design for an Identification Emblem, of which the following is a specification, reference being had to the accompanying drawing, forming part thereof.

The figure is a plan view of an identification emblem, showing my new design.

The article has no appreciable thickness.

I claim:

The ornamental design for an identification emblem as shown and described.

LAFAYETTE F. CARGILL,
